UNITED STATES PATENT OFFICE.

FRANK LUCKY KITTLE, OF CINCINNATI, OHIO.

RAILROAD-SWITCH-LOCKING MECHANISM.

Application filed July 29, 1927. Serial No. 209,354.

This invention relates to safety switch-locking devices used in railroad tracks to prevent tampering with the switch-throwing mechanism at any time and, more especially, 5 when the switch is in position for trains or traffic to pass freely therethrough without shunting. The object of the structure herein is to provide a reliable lock device for the said throwing mechanism that can be easily 10 shifted for the open and closed positions of the switch when it is properly set and not liable to be changed accidentally in the movements of the trains nor subject to any ordinary or undue manipulation by unauthorized persons intent on injury to the person and property of those using the tracks. 15

The details of structure will be clearly defined in connection with the description of the accompanying sheet of drawings, in 20 which:—

Figure 1 is a perspective view of the lock box or receptacle in which my safety detaining or locking feature is inclosed and ready for application to working-place in a track; 25 Fig. 2, a longitudinal sectional elevation of the inclosing-box seen in Fig. 1, and showing the safety lock-mechanism in the position it takes when the switch is in either its open or its closed state, dependent on its 30 relative location in the track, to be used to the right or to the left of the main-line, as the case may be; Fig. 3, a transverse section taken on the vertical dotted-line 3, 3, of Fig. 2; and Fig. 4, a sectional plan taken on 35 the horizontal dotted-line 4, 4, of Fig. 2 and, also, of Fig. 3.

A indicates the base of the inclosing box or casing; B, the shallow vertical fore-wall thereof; C, the vertical rear-wall thereof; 40 and D, the horizontal cover or lid whose rear pendent portion d is hinged at d', d', to the upper rear edge of the said rear-wall C. The base A extends forwardly and rearwardly beyond the front and rear walls B and C, as best shown in Figs. 3 and 4, to impart the desired firm and steady footing to the switch-lock box herein that must of necessity and the very nature of its somewhat important and dependable use rest on 45 a sure and proper foundation, proof against any undue rocking, wabbling, or ordinary shifting. The pendent forewall e of the lid D rests upon the upper aligning edge of the shallow fore-wall B of the lock box or 50 casing, and a centrally-projecting staple E is provided for engagement by a slotted hasp 55 F on the forewall B and the loop of a padlock G that is properly under the control of authorized attendants only. Opposite end-walls H and I are provided in the body 60 of the box A, the lid D being provided with aligning end-walls h and i, respectively, as best seen in Fig. 2.

Thus far I have described the details of the incasing-member which may be varied at will and made, not essentially, but preferably, as shown. I will now, however, describe the details of the structure of the locking features of my invention that are protected within the said encasing-member 70 for safety against tampering with and any undue alteration of the switch from its intended use.

4 indicates the horizontal auxiliary draft-bar or connecting rod internal-connection 75 having a forked outward-extension 5 through the end-wall I of the casing, a hole 6 being provided in said extension 5 for the cross-bolt used in attaching the adjacent end of the ordinary switch-throwing connecting-rod (not shown). The auxiliary internal draft-bar 4 has a raised hump-formation 7 near its inner end 8, and lateral lugs or blocks 9 and 10 are provided on its face, 80 suitably spaced apart, as best seen in Fig. 2, and a recess or open slot 11 is provided along its lower edge, in approximate alignment with the said pair of blocks 9 and 10, for the reception of a raised stop-formation or thickened portion 12 that is preferably made 85 integral with the longitudinally-slidable auxiliary latch or detent-bar 13, the latter constituting the most essential member of the improvement herein. The stop-formation 12 is shorter than the length of the recess 11 for due compensating-allowance in the relative coaction of the said auxiliary internal draft-bar with the said detent-bar when using the lock-mechanism for the switch in either its open or its closed condition. In 90 Fig. 2 I show the said draft-bar in its outermost-extended position, for the open switch, for example, and the said auxiliary detent-bar in its innermost position for said open condition of the switch, assuming that the inclosing lock-box is placed in a corresponding relation in the track, of course, or reverse to suit a reverse relation. 14 is a raised longitudinal strip or horizontal flange 95 integrally formed or provided in the bottom 100 of the box or casing A and on which the said auxiliary detent-bar slides lengthwise.

A strip or bar 15 is secured by means of screws or bolts 16 and 17, or otherwise, on the inner face of the back-wall C of the box, parallel to the auxiliary draft-bar. The 5 upper edge of the latter has sliding, free frictional contact with the lower edge of the strip 15, and the hump or raised portion 7 of the draft-bar engages an open slot or recess 18 provided in the lower edge of the strip 15, which slot 18 is longer than the length of said hump 7 and allows for a limited, sliding, reciprocal movement of said hump to suit the length of stroke of the draft-bar in the adjustment of the switch, 10 from open to closed position, or vice versa. A pair of corresponding bell-crank arms J and K is provided in the box A, the screws or bolts 16 and 17, respectively, being used to secure them in pivotal place, with intermediate washers to reduce friction, as customary, on the face of aforesaid rigid strip or bar 15. It will be noted, in Fig. 2, that all the securing-screws of the lugs 9 and 10 and of the bell-crank arms J and K are 15 on the same level, in due horizontal alignment, so that the hook-ends 19 and 20 of said crank-arms J and K, respectively, shall always engage the inner ends of said lugs 9 and 10 in a direct radial line with the pivotal centers of the bell-cranks provided by said bolts or screws 16 and 17. The said hook-ends 19 and 20 of the crank-arms are pivotally-mounted at the inner ends of their horizontal portions, by screws 21, and presser-springs 22 are provided on the hook-ends that extend into sockets in the upper part 20 of the corner or angle 23 of each bell-crank arm J and K so that said hook-ends are held under pivotal-tension for ready "snapping" 25 into engagement with the inner ends of the said lugs 9 and 10 when the locking device is in using-place for either the open or the closed condition of the switch, as the case may be.

30 A pair of two links 24, 25, are pivotally-connected together at their approaching inner ends by means of a bolt 26, and likewise pivotally-connected at their outer ends by means of bolts 27 to the lower forked ends 28 of the pendent members of the crank-arms J and K adjacent the face of the detent-bar 13, the said bolt 26 being also used to pivotally-connect the said inner ends of the said links 24, 25, to the detent-bar in a vertical line just below the middle of the compensating stop-bar 12, as best seen in Fig. 2, and thus coupling the detent-bar with said bell-crank arms for operating them into alternate engagement with their hook-ends 19, 20, in contact with the lugs 9 and 10, respectively, for the said open and closed 35 positions of the switch.

40 In Fig. 2 I have shown the device in locked position for an open switch, (assumed, as above stated,) the auxiliary inter-

nal draft-bar not being slidable in either direction without first sliding the detent-bar 13 outwardly so as to release the hook-end 20 of the crank-arm K from locked engagement with the lug 10. In the movement of 45 the detent-bar 13 the two hook-ends 19 and 20 are first brought to about the same upper or raised level when the draft-bar is to be manipulated in either direction for either the open or the closed position of the switch, 50 after which the detent-bar is further slid lengthwise (to the left outwardly) which causes the stop-formation 12 to bear against the end 29 of the recess 11 and fully closing the gap between the hump 7 of the draft-bar and the end 30 of the slot or recess 18 in the rigid strip 15 and stopping any further movement of the draft-bar, which coincides with either the full closing or the full 55 opening of the switch, as may be.

60 The auxiliary detent-bar 13 has a forked outer-extension 13^a that is adapted for engagement with the armature of an electric-motor, or otherwise, with the lever-connection of a compressed-air lever-throwing device, both in common use on railroads in throwing switches from towers or the like along the tracks. The said forked end 13^a and the electric or compressed-air actuating connections are suitably encased (not 65 shown) against intrusion or tampering by unauthorized persons intent on causing trouble and damage. Of course it will be readily seen that the outer forked end 5 of the draft-bar can be connected with the connecting-rod of the ordinary ground throw-stands of switches instead of the tower connections named.

70 Cotter-pins (as best seen in Fig. 2) are preferably used instead of nuts on all the 105 pivotal points in the structure, for both safety in use and facility in assembling or separating the parts thereof. It will be seen that the strip 15, the draft-bar 4, the detent-bar 13 and the raised bottom-strip 14 are all of the same uniform thickness of 75 material for due uniformity, and that the pivots 16 and 17 are on the same level with the centers of the fastening-screws of the lugs 9 and 10 so that when the hook-formations 19 and 20 of the bell-crank arms J and K are in alternate engagement with the said lugs they are not off-center with said lugs and the desired engagement of the hooks with the lugs is always available and effective 110 in the proper locking relation of the draft-bar with the detent-bar in safely and positively holding the switch in either open or closed locked position.

115 The device is extremely simple, easily approached by the authorized person for inspection, lubrication and repairs and not easily gotten out of order or deranged in use.

120 I claim:—

1. In a railroad-switch safety-lock mecha- 125

nism, the combination of an inclosing-box having an accessible lock-secured lid, a reciprocable auxiliary draft-bar mounted to slide within the said box and having a raised 5 formation or hump on its upper edge adapted to engage a recessed strip on the inner face of the rear wall of the box, lateral stop-means on the said hump, a recess in the lower edge of said auxiliary draft-bar, an auxiliary detent-means in reciprocal sliding 10 relation with said auxiliary draft-bar and having a raised formation adapted to engage the said lower recess in the draft-bar, hook-ended levers pivotally-mounted in the box 15 for alternate locking-engagement with said lugs on the draft-bar, and link-means pivotally-coupled at their inner ends to the said detent-means and at their outer ends to said hook-ended levers, the said auxiliary draft- 20 means and auxiliary detent-means having ends that extend outwardly from the opposite ends of the box for coupling with the draft-rod of the switch at one end of the box and with the lever or crank of an ar- 25 ture or other concealed power actuating device at the other end of the box for use in adjusting the lock in due relation with the position of the switch.

2. In a railroad-switch locking-mechanism, the combination of a box or casing 30 having an accessible lock-secured lid, a draft-bar having a raised portion or hump,

a stationary strip provided on the inner face of the casing and having an upwardly-extending recess of lesser length than that of the said hump on the draft-bar and forming 35 the upper edge of a guideway for said draft-bar with said hump in reciprocal-engagement with said recess, lateral lugs on the face of said hump, a vertically-aligned recess 40 in the lower edge of said draft-bar, a pair of bell-crank arms pivotally-mounted on the said stationary strip and having resiliently-mounted upper hook-ends adapted to alternately engage the said lateral lugs on 45 the hump, a detent-bar adapted to slide or reciprocate in parallel relation to said draft-bar and having a raised stop-formation coinciding with said lower recess in the draft-bar but of lesser length, and a pair of link- 50 levers pivotally-connected at their inner ends to the detent-bar centrally beneath said raised stop-formation and having pivotal-connection with the pendent lower ends of the said bell-crank arms, the said draft 55 means and detent means having respective outward extensions that are adapted to connect with any suitable power means to actuate said detent-bar into locking-engagement with said draft-bar, in either the open 60 or the closed positions of the switch.

In testimony whereof I hereunto affix my signature.

FRANK LUCKY KITTLE.
